UNITED STATES PATENT OFFICE

ROBERT K. WINNING, OF MILWAUKEE, WISCONSIN, ASSIGNOR TO CLUM MANUFACTURING COMPANY, OF MILWAUKEE, WISCONSIN

SWITCH BARREL AND THE LIKE AND METHOD FOR ITS MANUFACTURE

Application filed February 11, 1924. Serial No. 692,015.

This invention relates to improvements in the art relating to switch barrels and the like and methods for their manufacture. The invention is applicable to many different devices in which relatively movable parts are to be maintained in properly spaced relationship through an interposed body member or barrel.

In a switch mechanism it is very desirable that the relatively fixed plate containing the stationary contact and a relatively movable plate containing one or more movable contacts shall be properly spaced and in absolute parallelism, so that in passing from one fixed contact to another the movable contact will always remain operatively in the same plane. In the past, barrels constructed to contain a switch mechanism and the like have been made by various methods other than that herein disclosed, and it has been a general rule that in order to secure the desired accuracy such barrels have had to be milled or otherwise surfaced subsequent to their initial formation.

Broadly speaking, it is my primary object to cheapen the manufacture of switches and the like. More specifically stated, it is my object to provide a simple and inexpensive method of manufacturing a switch barrel in a manner such that it will be absolutely true and accurate as soon as formed and will, therefore, not require the comparatively expensive manually controlled finishing or surfacing operations which have heretofore been necessary.

I propose to satisfy the above mentioned objects by constructing a switch casing from stampings, the switch barrel being cut out in the form of a flat blank and subsequently 40 rolled to shape. I am aware that stamping processes have been widely employed in various manufacturing fields, but I do not know that anyone has heretofore constructed lock barrels or casings after the method 45 herein disclosed, nor do I believe that anyone has heretofore appreciated the startling economy effected by this method and due primarily to the fact that the opposite margins of a stamping may be made absolutely 50 parallel so that when said stamping is rolled

to comprise a cylinder its ends will have their entire peripheral extent in perfectly parallel planes.

Other objects of this invention are to provide a switch construction in which assembly is facilitated by wholly eliminating the bolts and nuts which are commonly employed; to provide a switch construction in which the cylinder blank will be maintained in its proper shape through interaction with the end plates which comprise therewith the switch casing; to provide a construction in which the several blanks comprising the switch casing can be assembled but one way and will be provided with visible tactile indicia, whereby the workmen may lose no time in assembly.

In the drawings:

Figure 1 is a front elevation of a lock switch embodying this invention.

Figure 2 is a sectional view taken on line 2-2 of Figure 1 and illustrating said switch in process of assembly, the back thereof being only partially in place.

Figure 3 is a developed view of the blank from which the barrel portion proper of the switch casing is formed.

Figure 4 is a top plan view of the completed barrel portion of the casing.

Figure 5 is a side elevation of said portion.

Figure 6 is a rear elevation of said portion.

Figure 7 is a rear view of the assembled switch casing.

Like parts are identified by the same reference characters throughout the several views.

The switch casing or barrel which, in its entirety will be called hereinafter the casing, comprises a tubular member 10 which will hereinafter be termed the barrel, a relatively thin stamped metallic disk 11 comprising a front plate for the casing, and a relatively thick fiber disk 12 comprising the rear end wall of the casing. The front margin 13 of barrel 10 is provided with a series of tongues which may be disposed at substantially regular intervals, tongues 14 and 15 being located immediately adjacent the end margins of the blank from which the barrel is formed, the tongues 16 being intermediate tongues 14 and 15. The rear margin 17 of the barrel is pro-

vided with a series of irregularly spaced tongues 18. The tongues 18 are all connected with the barrel by means of peripherally enlarged base portions, as indicated at 20, each 5 tongue proper 18 being of less peripheral extent and projecting beyond its base portion. At one point there is a base member 19 having no tongue. The reason for this unsymmetrical construction will be disclosed here- 10 inafter.

The disk 11 is provided at 60° intervals with arcuate slots 22 of slight extent. These slots are of such a size and are so disposed as to be adapted to receive tongues 16 when the 15 formation of the barrel is complete. At one point in the periphery of the disk there is a slot 23 having twice the peripheral extent of slot 16 and thereby rendered of sufficient size to receive both of the tongues 14 and 15 at 20 the two ends of the blank from which the barrel is formed. It will be noted from the disclosure in the drawings that when the barrel is rolled into shape, tongues 14 and 15 will be brought adjacent each other so that 25 when these tongues are received in slot 23 the barrel will be maintained with its ends 24 and 25 in abutment. The several tongues 14, 15, and 16 are bent downwardly upon the outer surface of the barrel (and preferably radially 30 outwardly from the slots 22 and 23 through which they project), and thereby serve to secure the disk 11 and barrel 10 rigidly together.

It is impractical to form slots of small dimensions in a fiber disk. Consequently, the disk 12 instead of being slotted is provided with broad shallow notches in its periphery at irregular intervals corresponding with the spacing of the bases 19 and 20 which project 40 rearwardly from the margin of the barrel. The preferred positions of these bases and notches are indicated in degrees in Figure 6. The bases fit into their respective notches like keys to secure the fiber disk 12 and the barrel 45 against relative rotation and, due to the irregular spacing of keys and notches, there is but one position in which the parts can be assembled. Due to the fact that the keys 20 are disposed in notches in the fiber disk 12, 50 the unnotched peripheral portions of said disk will abut the margin 17 of the barrel just as the disk 11 abuts margin 13 thereof. The tongues 18 are now bent inwardly over those portions of the fiber disk 12 adjacent the 55 notches and, as a result, the fiber disk is rigidly and permanently attached to the barrel 10 of the casing in perfect parallelism with disk 11.

Within the casing thus formed of barrel 60 10 and disks 11 and 12, any type of switch mechanism may be mounted satisfactorily. The fact that disks 11 and 12 are in absolute parallelism ensures the satisfactory operation 65 of the switch, since no amount of rotation of a moving contact journaled in or car-

ried by disk 11 will bring such contact either nearer to or farther from the surface of fiber disk 12 in which stationary contacts are disposed.

In the particular device herein illustrated 70 two switches are disposed in the casing. This device is particularly adapted for use upon the dash of a motor vehicle, and consequently the two switches housed by the casing are intended to control respectively the 75 ignition and the lighting circuits of the vehicle. These switches will not be described in detail, since the advantages of this construction will obviously be realized fully when any standard type of switch of the 80 general character described is employed. A brief description, however, of this particular switch is set forth in the following paragraphs.

The fixed contacts of both switches are 85 disposed in disk 12 and comprise internally threaded metallic sleeves 27 which, for the purposes of this description, need not be identified individually. Generally speaking, however, the contacts of the ignition switch are disposed centrally of disk 12, while the contacts for the lighting switch are disposed nearer the periphery of said disk. Thus, the single sleeve 27 illustrated in Figure 2, is a fixed contact in the ignition cir- 90 95

A pin 28 projecting inwardly from disk 12 centers a rotor including a dished actuating plate 29, insulating plates 30 and 31, and a metallic conducting element 32 supported by springs 33 from the insulating plates 30 and 31, the latter being formed with recesses to provide seats for the springs. The conducting member 32 is provided with spherically rounded protuberances 35 which, in 100 predetermined positions of rotation of the entire moving contact rotor, may be brought into registry with the sleeve-like stationary contacts 27. In the present device a lock barrel 36 secured to the face of disk 11 contains a lock of which 37 is the key. The proper key, when inserted in the lock, will be rotatable therein and its extremity 38 will engage in the dished member 29 to rotate the movable contact device of the ignition switch. 105 It may be added that the cap member 29 is so arranged that its cylindrical portion, as indicated in Figure 2, will be received within an annular flange 39 formed in disk 11, whereby the moving contact rotor of the ignition switch will be guided for rotation on an axis 110 normal to the face of disk 11. 115

The lighting switch includes a moving contact which comprises an annulus surrounding the moving contact rotor of the 125 ignition switch. This annulus includes a supporting member 40 having a portion 41 in face contact with the inner face of disk 11. The supporting member carries a pair of insulating annuli 42 and 43 from which a con- 120 125

ducting ring 44 having contact protuberances 45 is supported by means of springs 46. It will be understood that the protuberances 45 may be brought, by the rotation of the 5 entire annular rotor, into operative registry with certain of the tubular stationary contacts 27 carried by disk 12. Headed posts similar to that shown at 46 may be disposed at predetermined intervals to retain the circular 10 contact member 44 within a given distance from the fiber plate 43. This distance may be lessened, however, when the protuberances 45 ride out of the stationary contact sleeves against the compression of 15 spring 46. The annular rotor receives motion from a cap 50 having a handle 51. This cap encloses the lock barrel 36 and has an annular flange 52 which seats against the outer surface of disk 11. The cap is retained in 20 contact with said disk through the medium of a retaining ring 53 provided at intervals with tongues extending through suitable apertures in disk 11 and upset inwardly of said disk, as indicated at 55. Similar tongues 25 struck from cap 50 project through arcuate slots 56 in disk 11 and are engaged through apertures 57 in the portion 41 of the annular supporting member 40. Thus, upon the rotation of cap 50 within its retaining member 30 53, the oscillation of the cap will be transmitted through the said tongues to the annular moving contact rotor or the lighting switch. In various positions of such rotor the protuberances 45 and the intermediate 35 portions of the conducting ring 44 will establish operative electrical connections between selected stationary contact sleeves 27 in fiber disk 12.

While the simplicity and cheapness of construction of the switch mechanism herein disclosed will be obvious, it must likewise be clear that the more expensive and accurately fitted the switch mechanism may be, the greater will be the need for absolute accuracy of parallel alignment of the end surfaces of the barrel. Consequently, in a broad aspect, it is immaterial to this invention whether the particular mechanism herein disclosed is mounted within the switch casing or whether any other known type of switch is used. In fact, I do not desire to limit this invention solely to use in connection with the construction of switches since many types of locks and latches are dependent for their successful and accurate operation upon the alignment of the ends of their enclosing casing, and in all such mechanisms it will be advantageous to construct the barrel of the casing in the manner herein disclosed.

As indicated above, this invention pertains not only to the construction of the switch casing but also to the method by which it is constructed.

One of the most important features of

the method consists in manufacturing the barrel 10 by a stamping and rolling operation. In Figure 3 I have illustrated the appearance in plan of the stamped blank from which the barrel is rolled. In the rolling operation, which may be performed manually but is preferably accomplished by machinery, the two ends 24 and 25 of the blank are brought together so that the ears or tongues 14 are in immediate proximity. The appearance of the rolled barrel is clearly shown in Figures 4, 5, and 6. Thereafter the disk 11, which has previously been stamped to determine its form and to provide therein the several apertures required for tongues 14, 15, 75 16 and others, and to provide the flange 39, is now positioned with respect to the barrel in such a way that the single large aperture therein registers with tongues 14 and 15 which, at this time, project in an axial direction. The remainder of tongues 16 will then register accurately with their respective apertures 22, and disk 11 may be pressed into place to contact firmly with the entire periphery 13 of the barrel. With the disk 90 and the barrel in firm contact, tongues 14 and 15 are bent outwardly to connect these members in permanent fashion. It might be possible to bend the tongues upwardly to disconnect such members, but the tongues are 95 not intended for this purpose, since, if bent repeatedly, they must ultimately crack off. With disk 11 and barrel 10 thus assembled, it will obviously be impossible for the end margins 24 and 25 of the barrel blank to 100 become separated due to the fact that tongues 14 and 15 are retained in a slot 23 which is 14 sufficiently large to receive them.

As previously noted, the base members 20 really comprise keys and are at this time projecting axially from the barrel. Furthermore, they are unequally spaced about the periphery of the barrel, as indicated in Figure 6. The fiber disk 12, having been previously formed with notches to receive these keys, 110 and the switch mechanism or mechanisms having been assembled within the barrel, the disk 12 is now set in place with its central pin 28 projecting into the receiving aperture in the rotor of the central switch. In order to ensure that the switch rotor, in its various operative positions will make operative contact with the desired terminals in disk 12, it is essential that the disk be so assembled to the barrel as to make possible only one setting 115 or relative position of these members. This is the purpose for which the keys 20 are irregularly spaced about the periphery of the barrel, but if it were not for the provision of some sort of tangible indicia on the barrel 120 and the disk 12, the workman might spend considerable time in testing the various apparent positions of the disk with reference to the barrel to discover, by trial and error, the correct position at which these parts may 125 130

be assembled. To avoid loss of time in assembly, I preferably provide disk 12 with some mark adjacent its periphery at the point on said disk which is to be brought opposite to that base 19 which carries no tongue 18. Thus, it will be understood that a tongue 18 is omitted from base 19 to distinguish said base from the bases 20, and the disk 20 is correspondingly marked to identify that portion which is intended to be brought into registry with the distinguished key 19.

Of course, any desired identification mark on disk 12 may be used, but in order to avoid putting a special mark on the disk for this purpose, I prefer to place thereon the identifying number of the lock, which would at all events have to appear at some point on the lock. This number, as indicated in Figure 7, is so disposed that in addition to its primary function as a number it serves also, by its position of application, to facilitate the lock assembly.

Having described my invention, both as regards to the construction of a casing embodying this invention and the method by which such a casing is assembled, I wish to call attention once more to the fact which has heretofore been reiterated in the above description, that inasmuch as the blank from which barrel 10 is formed is made by a stamping or equivalent operation, there can be no doubt as to the parallelism of the margins 13 and 17 of said blank, and thereby absolute accuracy of performance of the lock is ensured without any necessity for hand work or milling work on said barrel. The end surfaces of the barrel may, by the same method and with equal accuracy, be formed in angular planes.

I claim as my invention:

1. In a device of the character described, a tubular barrel having a cut from end to end in its wall, tongues integrally connected with said barrel adjacent the margins of said cut on opposite sides thereof, and a disk closure secured to the end of said barrel and provided with means to receive said tongues and to key said tongues together, whereby to maintain said barrel in tubular form, the engagement of said tongues in said disk constituting the sole means at said end of the barrel for maintaining the margins of the barrel together.

2. In a device of the character described, a split ring having tongues projecting axially from its marginal portions adjacent the split therein, and a closure for one end of said ring provided with spaced shoulders adapted to abut opposite sides of said tongues and to maintain the ends of said split ring in substantial abutment.

3. In a device of the character described, the combination with a split ring having axially projecting tongues adjacent its ends and intermediate tongues at spaced intervals

about its periphery, of a disk provided at intervals corresponding with the spacing of said intermediate tongues with apertures of size just sufficient to receive said intermediate tongues, and provided at a proper point with an aperture of just sufficient size to receive said first mentioned tongues, all of said tongues being bent about portions of said disk adjacent said apertures, whereby said disk is secured to said ring and the ends of said ring are secured by said disk against separation, said disk extending beyond the periphery of said ring whereby the engagement of said tongues in the apertures of said ring maintains the form of said ring and secures its marginal portions against separation.

4. In a device of the character described, the combination with a disk carrying a fixed contact, and a disk provided with a movable contact member; of an intermediate barrel maintaining said disks in substantial parallelism and having unfinished marginal portions abutting said disks, said barrel having integral tongues interlocked with the respective disks and upset upon the outside faces of the disks, whereby to secure said disks upon the barrel.

5. In a device of the character described, the combination with a disk provided with a fixed contact member and a disk provided with a movable contact member, of a barrel split from one end to the other and provided with tongues interlocked with one of said disks, two of said tongues being immediately adjacent and at opposite sides of the split in said barrel whereby its form is maintained, said disks being pressed into contact with the ends of said barrel, and such ends being in substantially exact parallelism, whereby said members are uniformly operative.

6. In a device of the character described, the combination with a disk provided with a fixed contact member, of a second disk, a movable member adjustable with respect to the second disk and having its plane of adjustment defined thereby, and a rolled sheet metal axially split barrel having unfinished end surfaces in substantially exact parallelism and axially projecting lugs bent into engagement with the respective disks and positioned in apertures therein, said disks being retained thereby in abutment with opposite end surfaces of said barrel and two of said lugs being closely adjacent the portions of said barrels adjacent the split therein, and closely confined between opposing shoulders of one of the disks, whereby the form of said barrel is maintained and said members will be uniformly operative.

7. In a device of the character described, a barrel split from end to end and provided with axially projecting tongues at one end and with keys irregularly spaced peripherally about the other end and projecting

axially therefrom, said keys being provided with tongue portions extending beyond the keys, a disk clamped in engagement with the first mentioned end of said barrel and provided with apertures receiving said tongues,
5 the extremities of said tongues being bent about adjacent portions of said disk, and a second disk of insulating material provided with notches in its margins adapted to receive said irregularly spaced keys, the tongues projecting from said keys having portions bent about said second disk to retain said second disk with its unnotched marginal portions in contact with the barrel.
10 8. In a device of the character described, a barrel split from end to end and provided with axially projecting tongues at one end and with keys irregularly spaced peripherally about the other end and projecting
20 axially therefrom, said keys being provided with tongue portions extending beyond the keys, a disk clamped in engagement with the first mentioned end of said barrel and provided with apertures receiving said tongues, the extremities of said tongues being bent about adjacent portions of said disk, a second disk of insulating material provided with notches in its margins adapted to receive
25 said irregularly spaced keys, the tongues projecting from said keys having portions bent about said second disk to retain said second disk with its unnotched marginal portions in contact with the barrel, and a key distinguished from the other keys on said barrel by
30 the absence of a tongue thereon, said last mentioned key being received in a suitable notch in said last mentioned disk, and said disk being provided with an identifying mark arranged to lie adjacent said key.
